UNITED STATES PATENT OFFICE.

EUGENE GREGORY, OF MICHIGAN CITY, INDIANA, ASSIGNOR TO NATIONAL FRESH AIR FURNITURE COMPANY, OF RENO, NEVADA, A CORPORATION OF NEVADA.

COUCH-HAMMOCK.

1,032,540.

Specification of Letters Patent.

Patented July 16, 1912.

Application filed October 27, 1911. Serial No. 657,101.

To all whom it may concern:

Be it known that I, EUGENE GREGORY, of Michigan City, in the county of Laporte and State of Indiana, have invented certain new and useful Improvements in Couch-Hammocks; and I hereby declare that the following is a full, clear, and exact description thereof, reference being had to the accompanying drawings, which form part of this specification.

This invention is a novel couch hammock and its object is to provide an adjustable couch hammock, preferably having a spring bottom; and which can have its ends adjusted so that the occupant may be supported in a reclining or sitting position; or the spring bottom can be flattened out so that the hammock may be used as a bed or couch.

The invention consists in the novel construction of the hammock and parts thereof as hereinafter summarized in the claims, and I will describe the same in detail with reference to the accompanying drawings in which—

Figure 1 is a side view of the hammock in its flattened or extended position. Fig. 2 is a plan view of Fig. 1. Fig. 3 is an enlarged detail side view of one part of the hammock showing one end thereof adjusted to reclining position. Fig. 4 is a similar enlarged view showing the parts adjusted to sitting position. Fig. 5 is an end view of Fig. 1. Fig. 6 is a side view of the hammock folded for transportation. Fig. 7 is a detail view of a wire spring.

The hammock comprises a base frame composed of side bars 1 and end bars 1^a which may be suitably united and braced at the corners by straps 1^b. The frame 1 is strengthened and reinforced by means of transverse truss-members each comprising a transverse bar 2, end uprights 2^a which are attached to the ends of the bar 2, and braces 2^b may be connected to the uprights 2^a and bottom bar 2 as shown in Fig. 5. The upper ends of the uprights 2^a are preferably attached to the side bars 1 of the frame at equidistant points from the ends thereof by means of bolts 2^c so that for transportation the members 2 may be folded flat within the frame 1, see Fig. 6. Truss-rods 2^d are attached to the opposite ends of each bar 1 by means of bolts 2^e and to the under side of each truss-frame below the end of the uprights 2^a as shown in the drawings. This

construction forms a very stiff but light frame and will not interfere with the flexing of the spring mattress which is secured to and over the frame.

Supported upon the main frame 1, 1^a, is an auxiliary mattress frame, comprising central side members 3 attached to the bars 1 and side members 3^a which are hinged to each end of the members 3 as shown at 3^b. The outer ends of the opposite side members 3^a, at each end of the hammock, are connected by end bars 3^c; and these sections may be braced at the corners by straps 3^d. Any suitable cover or seating may be employed and connected to this frame. A spring mattress is shown in the drawings. This mattress preferably being constructed substantially as shown and described in my application Serial Number 632,721, filed June 12, 1911. As shown in the drawings the mattress or bed bottom fabric is composed of wire rings 4 and wire springs 5; each spring 5 (except those at the outermost sides of the fabric) is interposed between and connects two adjacent rings 4. Each spring 5 is preferably made of a single stiff steel wire which is bent intermediate its ends into an approximately figure 8 shape, forming two flat loops 5^a (Fig. 7) lying in substantially the same plane, while the two ends of the wire 5^b extend in opposite directions from between the loops but in substantially the same plane; and the extremities of these ends or arms 5^b of the spring are hooked as at 5^c, to engage the rings. The outermost spring members 5 at the sides and ends of the wire bottom are connected to the adjacent side bars 3, 3^a and end bars 3^c of the auxiliary frame. As shown wire springs 6 are attached to the side bars 3, 3^a; and to the outer rings 4; while the outer arms of the outermost end spring-members 5 may be connected to the loops on the ends of the frame by means of wire links 6^a; I have found it is unnecessary in practice to extend the spring fabric the entire length of the frame, it being sufficient if it extends under such portions of the cover or seating as will be subjected to the weight of a person lying thereupon, and the intermediate portions may be of the usual wire mattress construction as indicated in the drawings. The construction of the seating, cover, or mattress does not constitute any part of the present invention and further explanation

thereof is unnecessary. By reason of the hinge connection of the members 3^a either end of the seating can be adjusted to different positions, as indicated in Figs. 2 and 3 5 of the drawings.

As shown, frame 1 may be provided at its ends with hooks 1^e which may be engaged by the cords or chains 1^f by which the hammock is suspended in the usual manner. I 10 also provide the hammock with rectangular end frames consisting of side members 4 and top and bottom members 4^a suitably connected together; and I also preferably connect said members by an intermediate 15 cross piece 4^b. The end frames are provided at their upper corners with hooks or eyes 4^d which may be engaged with links of the suspending chains 1^f as shown so as to hold the frames 4 in vertical position. The lower 20 ends of the frames 4 are held in position by bayonet-shaped irons or hooks 4^e which are adapted to engage the outer end bars 3^b, as indicated in Figs. 1 and 4.

To the side members 4^a of the end frames 25 are attached one or more outwardly projecting studs 4^f which when the frames are in vertical position (Fig. 1) engage the chains 1^f and prevent the lower portions of the end frames swinging outward past the chains. 30 The studs 4^f also serve another purpose, to wit, when it is desired to adjust either end of the mattress to inclined (reclining) position, see Fig. 3, its end is raised until hooks 3^e (attached to the outer ends of the adjacent auxiliary side bars 3^a) can be engaged 35 with the studs 4^f, and thus support the end of the mattress in the position shown in Fig. 3. If it is desired to adjust the hammock to 40 sitting position, one end of the auxiliary frame (3^a, 3^b) is raised to the position shown in Fig. 4, and the adjacent end frame 4 is swung upward until the hooks 4^e on such frame can be caught over the end bar 3^b of the adjacent auxiliary frame section. In 45 this position the occupant of the mattress will be supported in a sitting position.

Obviously if both ends of the auxiliary frame are made adjustable, as described and shown, either end of the seating can be adjusted to a reclining or a sitting position; and this adjustment can be made quickly and easily. In some forms of hammocks only one end of the auxiliary frame is adjustable. When both ends are made adjustable the construction is simply duplicated at each end of the hammock.

When it is desired to transport the hammock the ends of the auxiliary frame are laid flat upon the supporting frame and the 60 two end frames may be laid thereover. The truss-rods 2^a may be loosened and discon-

nected from the truss-members 2, and the latter may then be folded up within the hammock frame as indicated in Fig. 6 of the drawings.

65

What I claim is:—

1. In a hammock the combination of a main frame, means for suspending said frame, an auxiliary frame mounted thereupon, a seating or cover attached to said auxiliary frame; and an end-frame adjustably mounted at the end of the main frame, and adapted to support the auxiliary frame in different positions.

2. A hammock comprising a main frame, means for suspending the main frame, an auxiliary frame mounted thereupon, the end of said auxiliary frame being hinged; an end frame adjustably mounted at the ends of the main frame, and engaging means on the end frame and said auxiliary frame for supporting the latter in different adjusted positions.

3. In a hammock the combination of a main frame, means for suspending said frame, an auxiliary frame mounted thereupon, the end of said auxiliary frame being hinged, a seating or cover attached to said auxiliary frame; an end frame adjustably mounted at the end of the main frame, and means on said end frame for engaging and supporting the end of said auxiliary frame in adjusted positions.

4. In a hammock the combination of a rigid main frame, truss members and truss rods bracing the under side of said frame, an auxiliary mattress frame mounted on the main frame the ends of said auxiliary frame being hinged, a seating connected to said auxiliary frame, and means for supporting the ends of the auxiliary frame in adjusted positions.

5. In a hammock the combination of a rigid main frame, truss members and truss rods bracing the under side of said frame, an auxiliary mattress frame mounted on the main frame, the ends of said auxiliary frame being hinged; a seating connected to said auxiliary frame, end frames adjustably mounted at the ends of the main frame, and engaging devices on the end frames and the adjacent hinged ends of the auxiliary frame; whereby the latter may be supported in different adjusted positions, substantially as described.

In testimony that I claim the foregoing as my own, I affix my signature in presence of two witnesses.

EUGENE GREGORY.
